(57) **CLAIM**

The ornamental design for the jewelry packaging, as shown and described.

DESCRIPTION

FIG. 1 is a front isometric view of jewelry packaging showing a first embodiment of the new design in a closed configuration.

FIG. 2 is a front isometric view thereof in an open configuration.

FIG. 3 is a bottom isometric view thereof in the closed configuration.

FIG. 4 is a bottom isometric view thereof in the open configuration.

FIG. 5 is a front elevational view thereof in the closed configuration. The rear elevation view is a mirror image of the front elevation view.

FIG. 6 is a front elevational view thereof in the open configuration.

FIG. 7 is a right-side elevational view thereof the closed configuration. The left-side elevation view is a mirror image of the right-side elevation view.

FIG. 8 is a right-side elevational view thereof the open configuration.

FIG. 9 is a top plan view thereof.

FIG. 10 is a bottom plan view thereof.

FIG. 11 is a front isometric view of jewelry packaging showing a second embodiment of the new design in a closed configuration.

FIG. 12 is a front isometric view thereof in an open configuration.

FIG. 13 is a bottom isometric view thereof in the closed configuration.

FIG. 14 is a bottom isometric view thereof in the open configuration.

FIG. 15 is a front elevational view thereof in the closed configuration. The rear elevation view is a mirror image of the front elevation view.

(Continued)

FIG. 16 is a front elevational view thereof in the open configuration.

FIG. 17 is a right-side elevational view thereof the closed configuration. The left-side elevation view is a mirror image of the right-side elevation view.

FIG. 18 is a right-side elevational view thereof the open configuration.

FIG. 19 is a top plan view thereof; and,

FIG. 20 is a bottom plan view thereof.

The broken lines in the drawings are for the purpose of illustrating portions of the jewelry packaging that form no part of the claimed design. The jewelry packaging is shown with symbolic breaks in its height in FIGS. 1-8, represented by break lines. The break lines and appearance of any portion of the article between the break lines form no part of the claimed design.
